Frank Schaefer Jr
Attorney.

UNITED STATES PATENT OFFICE.

CHARLES ELEMAN, OF CHICAGO, ILLINOIS.

TRUSS.

1,360,509.

Specification of Letters Patent. Patented Nov. 30, 1920.

Application filed April 2, 1918. Serial No. 226,187.

To all whom it may concern:

Be it known that I, CHARLES ELEMAN, a citizen of the United States, residing in the city of Chicago, in the county of Cook and

5 State of Illinois, have invented new and useful Improvements in Trusses, of which the following is a specification.

This invention relates to trusses and has particular reference to wooden roof trusses 10 and the like.

One of the objects of this invention resides in the provision of wood truss which is low in cost of material and construction; one which can readily be built in the field or site 15 of installation.

Another object of this invention is a wood truss which can be built from a number of light wood members.

With these and other objects in view my 20 invention consists in the novel construction, combination, and relative position of the parts and members shown in the accompanying drawings, hereinafter described, and particularly pointed out in the appended 25 claim.

Referring to the drawing in which like reference characters indicate like or corresponding parts:

Figure 1 is an elevation of my improved 30 truss. Fig. 2 is a cross section taken on line 2-2 of Fig. 1. Fig. 3 is an elevation taken on line 3-3 of Fig. 2, showing the center system of members indicated also by C in Fig. 2.

35 Fig. 4, is an enlarged detail of the framing at points R and S in the intermediate system of members B looking in direction of 4-4 in Fig. 2, and Fig. 5, is also an enlarged detail of the framing at points T and U in 40 such intermediate system of members B. In the drawings, A indicates the outer system of members. The truss is symmetrical about the center line 2-2.

Referring to the drawings which disclose 45 a form of truss construction and arrangement embodying my invention, and here shown as comprising five sections or systems of framing or members, I provide a center system C which comprises the two end horizontal abutment members 10 and the angular

larly disposed compression members 11, 12, 13, and 14 arranged for end to end abutment with each other and with said abutment members 10.

Within the top chord of the truss and between top abutting ends of said members 11, 12, 13, and 14, I provide the members 15 and 16.

55 Inasmuch as both systems A and B are alike, I shall confine my description to one system of each.

The intermediate system B, comprises in the lower chord the member 17 which extends from one end of the truss to the other, or the full length L. The upper chord member of system B comprises the four members 18 and 19. One end of member 18 rests upon the lower chord 17 and the other abuts with the member 20. One end of member 19 abuts with the opposite face of member 20 and the other end abuts with the end of its complementary member 19 at the center of the truss. The lower ends of the members 20 are inserted a few inches into the lower chord members 17. A tie rod 21 extends from the bottom to the top of the lower and upper chords and is placed between the faces of the systems A and B.

65 The outer system A, comprises in the lower chord, the member 22 which extends from one end of the truss to the other, or the full length L. The upper chord comprises members 23 and 24 arranged with abutting ends and running parallel with the intermediate similar members 18 and 19. Suitable bolts 80 25 and nails are provided for securing the members of the various systems together. Bent steel straps 26 extend from the face of one system A across the end of the truss to the face of the other system A. 90

It is obvious that the members shown and described may be made in any suitable lengths and spliced where desired.

95 It is thought that the foregoing description and illustrations clearly disclose the construction and operation of the invention, hence a more extended explanation is omitted.

I claim:—

100 In a truss, and in combination, a pair of

built-up sections having upper and lower chords and members in tension only connecting said chords, a center section comprising a plurality of angularly disposed abutting compression members 11, 12, 13 and 14, and horizontal end abutment members 10 confining said compression members, and members 15 and 16 extending between the upper

ends of said compression members substantially as shown and described.

10

In witness whereof, I have hereunto subscribed my name this 30th day of March, 1918.

CHARLES ELEMAN.
